CARBURETOR.

1,050,463.

Specification of Letters Patent. Patented Apr. 22, 1913.

Application Rec'd Aug. 14, 1912. Serial No. 216,269.

To all whom it may concern:

Be it known that I, Christian N. Johnson, a citizen of the United States, and a resident of Detroit, in the county of Wayne and State of Michigan, have invented a New and Improved Carbureter, of which the following is a specification:

This invention relates to means for carbureting air with gasoline and other liquid hydrocarbons for use as fuel for internal combustion engines, and its object is to provide a construction wherein the amount of air passing through the carburetor under different conditions can be accurately predetermined, and to provide a construction which shall be reliable in operation, strong, and positively adjustable for all conditions of service.

This invention consists in the combination of a float chamber and a carbureting chamber, of a cylindrical air-valve slidably mounted within the carbureting chamber, of manually adjustable means for controlling the position of the air-valve, and a positively adjustable disk for controlling the currents of air across and around the discharge orifice of the gasoline into the carbureting chamber.

In the accompanying drawings, Figure 1 is a central vertical section of the carburetor and Fig. 2 is an elevation of the same taken from the right in Fig. 1. Fig. 3 is an elevation of a portion of the body of the carburetor taken from the right in Fig. 1. Fig. 4 is a central vertical section of a portion of the carburetor at right angles to the one of Fig. 1. Fig. 5 is a section on the line 5-5 of Fig. 1. Fig. 6 is a section on the line 6-6 of Fig. 5. Fig. 7 is a section on the line 7-7 of Fig. 1.

Similar reference characters refer to like parts throughout the several views.

This carburetor consists of a carbureting chamber, a discharge tube extending upwardly therefrom, and a float chamber below the carbureting chamber, together with the different movable parts hereinafter described. The body 1 of the carbureting chamber has a cylindrical extension 2 provided with a circumferential groove 3. A tubular discharge pipe 4 connects at its upper end to the engine and its lower end fits this extension 2 and is provided with lugs 5 on each side of a slot 6, through which lugs a screw 7 extends and is threaded into one of the lugs in order to draw them together so as to firmly grip the extension 2.

As shown in Fig. 1, this screw 7 extends across into the groove 3. The discharge pipe 4 has inwardly extending collars 9 into which the inner tube 10 is tightly fitted. Pipes 12 and 13 connect to the circulating system of the engine so the circulating water may serve to heat the inner tube 10, and the explosive mixture passing through this tube 10 to the engine may be kept at a moderately high temperature. It has been found that the operation of the engine is more satisfactory during cold weather when the explosive mixture enters the engine thus heated. Extending across through the body 4 and inner tube 10 is a stem 14 on which the throttle-valve 15 is mounted. A lever 16 is secured on the outer end of this stem and carries an adjustable screw 17 adapted to contact with the abutment 18 when the throttle is entirely closed. This discharge pipe 4, inner tube 10 and valve 15 form no part of the present invention.

A diaphragm 20 forms the lower wall of the carbureting chamber and the upper wall on top of the float chamber, and is provided with a depressed portion 21 and a hub 22 into which a sleeve 23 engages. The outer end 24 of this sleeve is screw-threaded to receive the nut 25, which holds the bowl 26 securely and tightly against a flange 27 on the carbureting chamber. The upper end 28 of this sleeve 23 is formed into a discharge-nipple for the gasoline which enters the bore 29 of this sleeve through a small passage 20.

The lower end of this sleeve is internally threaded to receive the threaded portion of the stem of the needle-valve 30, which has a fluke or button 31 on its outer end. A stuffing box 32 of the usual type may be employed to prevent leakage around the stem 30. Extending downwardly from the nut 25 is a small lever 33 which carries a slidably mounted pin 34 held outwardly by the spring 35. The lower point of this pin is adapted to enter the notches 36 in the button 31, as shown in Fig. 7, and thus hold the button in the position in which it is placed to provide a proper flow of fuel from the nozzle 28. The upper end of the stem 30 will be tapered as shown in Fig. 1 in the usual manner. The construction of the bowl 26, the sleeve 23 and the needle-valve forms no part of the present invention.

The fuel-supply pipe 37 may connect in any desired manner, preferably to a passage

38, which has a reduced portion 39 connecting to the small vertical passage 40. Mounted in the lugs 42 is a pin 43 which carries a float 44 provided with a small metal arm 45 on which the valve 46 rests. So long as the level of the fuel is at the predetermined height, the valve 46 will be held upward by the float to close the passage 40, but when the fuel in the cup 26 falls, the passage 40 will be opened and the fuel replenished. The construction of the float and valve are well known.

Securely mounted within the cylindrical portion 2 of the carbureting chamber is a cylindrical tube 48 whose lower end 50 is conical and tapers downwardly, as shown in Fig. 1, to form what is termed a strangle-tube. This tube 48 has a series of openings as shown in Fig. 2 and Fig. 5, the bars 52 connecting the cylindrical portion 48 and the conical portion 50. Slidably mounted within this tube is a sleeve 53 having a ring 54 connected to it by means of bars 55 of substantially the same width and length as the bars 52 just mentioned. This sleeve is formed with a small perforation to receive the pin 56 on the inner end of the shaft 57, journaled in the side wall of the carbureting chamber, which pin has a milled head 58 on its outer end engaged by one end 59 of the spring 60, which spring will hold the head 58 in any desired position but will permit the turning of the same in order to adjust the height of the sleeve 53 and the ring 54. Vertically slidable in the sleeve 53 is a light, cylindrical air-valve 61 which has a spider 62 in its lower end formed by four cross-arms meeting at the center. A screw 63 is carried by this spider and is held in the desired position by means of a jam-nut 64. A small disk 65 is secured to the lower end of this screw 63 and extends down into the tapering strangle-tube 50 until it is almost in contact with the discharge end of the nozzle 28. The operation of this device is as follows.

Fuel will flow from the pipe 37 to the float chamber 26 in the usual manner and the float 44 is so constructed and adjusted that under normal conditions, when the engine is stopped, the upper end of the nozzle 28 will be above the line 66 of the fuel in the float chamber. The distance between the upper end of this nozzle 28 and the level 55 of the fuel in the float chamber will be such that, as soon as the engine begins to revolve and air rushes in through the passage 67 and down between the strangle-tube 50 and the depressed portion 21 of the diaphragm 20, and up through the strangle-tube, a slight vacuum will occur at the upper end of the nozzle 28, causing the fuel to flow out through this nozzle into the path of the inrushing air. The rush of the air 65 against and around the edge of the disk 65

on the stem 63, will lift this disk and with it the cylindrical valve 61. As soon as this valve leaves its resting place, that is the ring 54, air will also flow in through the openings between the bars 52 and 55. The height that this cylindrical valve will be lifted will depend upon the flow of the air around the disk 65, and when this flow of air decreases, the valve will immediately fall. In practice, the height of the valve is substantially stationary because of the balance attained between the weight of the valve and the upward urge of the current of air. The flow of the air between the strangle-tube 50 and the depression 21 and up through the strangle-tube itself over the nozzle 28, will vary substantially with the speed of the engine and the lift of the valve 61.

The throttle-valves 15 of carburetors are usually so constructed as to leave a slight opening around them so that an unloaded engine can slowly operate when the valve is in closed position. The amount of air which is drawn into the engine through the tube 10, and the amount of gasoline mixed therewith, will of course vary with the type of engine, and the amount of gasoline taken up by the inrushing air will depend upon the distance between the disk 65 and the top of the nozzle 28, the less the distance, the less fuel being taken up. This is for the reason that when the disk 65 leaves the upper end of the nozzle 28 under a greater rush of air, there results a slightly greater vacuum at the opening and a more rapid flow of fuel.

It is sometimes desirable to adjust the position of the disk 65 with reference to the nozzle 28 because of a difference in the fuel employed for operating the engine. In such case, the button 58 on the shaft 57 may be turned so that the crank-pin 56 will shift the sleeve 53 and the ring 54, thereby altering the distance between the nozzle 28 and the disk 65. As this adjustment can easily be made without taking apart the carburetor, the initial adjustment of the disk 65 can be made at the factory where the carburetors are produced. As the air which enters the passage 67 flows entirely around the cylindrical tube 48, the sleeve 53 and the tubular valve 61, the air will enter the different openings between the bars 52 and 55 and thoroughly mix with the air and fuel passing up through the strangle-tube and 115 through the spider 62 at the lower end of the cylindrical valve.

The details of construction of the various parts and the means of adjusting the same, as well as the proportions between them, may all be varied by those skilled in the art without departing from the spirit of my invention.

I claim,

1. In a carburetor, the combination with a 130

carbureting chamber consisting of an outer shell having a cylindrical upper portion, a cylindrical discharge tube secured therein, a float chamber below said carbureting chamber, the bottom of the carbureting chamber constituting a diaphragm separating the carbureting chamber and the float chamber and having a depressed central portion, a fuel-nozzle extending upward through said 5 depressed portion, a tapering strangle-tube extending down into said depressed portion with its lower end concentric with the upper end of the fuel-nozzle, means to support the strangle-tube, an adjustable cylindrical sleeve adjustably mounted within said supporting means and having downwardly extending bars connected thereto, a ring connected to the lower end of said bars, a cylindrical valve slidably mounted 10 within said sleeve and normally resting on said ring, a cross-bar at the lower end of said valve, a downwardly extending stem mounted in said cross-bar, and a disk on the lower end of said stem, said disk supported above and separated from the upper 15 end of said fuel-nozzle.

2. In a carbureter, the combination of a carbureting chamber, a float chamber secured thereto, the bottom of said carbureting chamber forming a top for the float chamber and having a central depressed portion, a fuel-nozzle extending upwardly through said depressed portion, a downwardly tapering tube mounted in said carbureting chamber concentric with said nozzle and extending down into said depressed portion, vertical bars supporting the tube, and a cylindrical valve mounted within said 20 bars concentric with said fuel-nozzle and adapted to be raised by the flow of air upward through said downwardly tapering tube.

3. In a carbureter, the combination of a body, a float chamber secured thereto, the bottom of the body forming a top for the float chamber and having a central depressed portion, a fuel-nozzle extending upwardly through said depressed portion, a downwardly tapering tube mounted in said body concentric with said nozzle and extending down into said depressed portion, vertical bars supporting the tube, a cylindrical valve mounted within said bars concentric with said fuel-nozzle, and a vertically adjustable ring 25 for supporting said cylindrical valve.

4. In a carbureter, the combination, with a carbureting chamber, a float chamber secured thereto, the bottom of the carbureting chamber forming a top for the float chamber and having a downwardly extending central portion, a fuel-nozzle extending from the float chamber through said central portion into said carbureting chamber, a cylindrical tube secured in the upper end of 30 said carbureting chamber, downwardly ex-

tending bars connected to said tube, a downwardly tapering tube connected to the lower end of said bars concentric with said fuel-nozzle, a vertically adjustable sleeve mounted within said bars and having downwardly extending bars, a ring connected to the lower end of said bars, and a cylindrical valve slidably mounted within said sleeve and bars and normally resting on said ring.

5. In a carbureter, the combination with a carbureting chamber, a float chamber secured thereto, the bottom of the carbureting chamber forming a top for the float chamber and having a downwardly extending central portion, a fuel-nozzle extending upward through said central portion into said carbureting chamber, a cylindrical tube securely mounted in the upper end of said carbureting chamber, downwardly extending bars connected to said tube, a downwardly tapering tube connected to the lower end of said bars concentric with said fuel-nozzle, a vertically adjustable sleeve mounted within said bars and having downwardly extending bars, a ring connected to the lower end of said bars, a cylindrical valve slidably mounted within said sleeve and bars and normally resting on said ring, a cross-bar mounted in the lower end of said valve, a screw adjustably mounted in said cross-bar concentric with said fuel-nozzle, and a disk mounted at the lower end of said screw within the tapering tube.

6. In a carbureter, the combination of a body having a plate provided with a centrally depressed portion constituting its lower side, a downwardly tapering tube mounted in said body, a fuel chamber mounted adjacent the body, a fuel-pipe connecting to the fuel chamber and to said plate to conduct fuel to said depressed portion, guide-bars supporting said downwardly tapering tube within said body, and a cylindrical valve slidably mounted above said tube and adapted to be raised by the flow of air upward through said downwardly tapering tube.

7. In a carbureter, the combination of a carbureting chamber having a bottom provided with a central depression, means for conducting fuel into said chamber at the center of said depression, a downwardly tapering tube rigidly mounted in said chamber and extending into said depression, a cylindrical valve slidably mounted within the chamber concentric with said tapering tube and adapted to be raised by the flow of air through said downwardly tapering tube, and means to guide said cylindrical tube.

8. In a carbureter, the combination with a carbureting chamber, a fuel reservoir adjacent thereto, the bottom of the body constituting a diaphragm having a downwardly extending central portion, a fuel-nozzle extending from said fuel chamber into said

- downwardly extending portion of the diaphragm, a cylindrical tube securely mounted in the upper part of said carbureting chamber and having air inlets, a downwardly tapering tube connecting to the lower end of said cylindrical tube and mounted concentric with said fuel-nozzle and extending into said downwardly extending portion of the diaphragm, a vertical adjustable sleeve mounted within said cylindrical tube and provided with air inlets and having a ring at its lower end, and a cylindrical valve slidably mounted within said sleeve and normally resting on said ring and closing the air inlets.
9. In a carbureter, the combination with a carbureting chamber, a fuel reservoir adjacent thereto, the bottom of the carbureter constituting a diaphragm having a downwardly extending central portion, a fuel-nozzle extending from said fuel chamber up into said downwardly extending portion of the diaphragm, a cylindrical tube securely mounted in the upper end of said carbureting chamber and having air inlets, a downwardly tapering tube connecting to the lower end of said cylindrical tube and mounted concentric with said fuel inlet and extending into said downwardly extending portion of the diaphragm, a vertically adjustable sleeve mounted within said cylindrical tube and provided with air inlets and having a ring at its lower end, a cylindrical valve slidably mounted within said sleeve and normally resting on said ring and closing the air inlets, a cross-bar mounted in the lower end of said valve, a stem extending downwardly therefrom, and a disk mounted at the lower end of said stem within said downwardly tapering tube, whereby the cylindrical valve may be raised to open said air inlets when the rush of air up

through the downwardly tapering tube is sufficient to carry the weight of said valve.

10. In a carbureter, the combination of a body having an air inlet opening in its side and a bottom provided with a central depression, said body having a cylindrical outlet connection, a fuel-nozzle connected to said body and discharging into said depression, a downwardly tapering tube extending into said depression, a cylindrical air-valve slidably mounted above the tube and extending upwardly into said cylindrical outlet connection of the body and adapted to be raised by the flow of air upward through said downwardly tapering tube.

11. In a carbureter, the combination of a body having an air inlet opening in its side and a bottom provided with a central depression, said body having a cylindrical outlet connection, a fuel-nozzle connected to said body and discharging into said depression, a downwardly tapering tube extending into said depression, a cylindrical air-valve mounted above the tube and extending upwardly into said cylindrical outlet connection of the body, a stem extending downwardly from the lower end of the valve, and a disk on the lower end of the stem within the tapering tube and in the path of air ascending in said tube, said disk so proportioned and positioned that the valve will be lifted when the upward flow of air exceeds a predetermined amount so as to admit air between the bottom of the valve and the top of the tapering tube.

In testimony whereof I have signed this specification in the presence of two subscribing witnesses.

CHESTER F. JOHNSON.
